UNITED STATES PATENT OFFICE.

HEINRICH ELSNER, OF DRESDEN, GERMANY.

MACHINE FOR CUTTING SEVERAL INDIVIDUAL CIGARETTES FROM PREVIOUSLY-CUT CIGARETTE RODS.

Application filed January 31, 1921. Serial No. 441,520.

To all whom it may concern:

Be it known that I, HEINRICH ELSNER, a subject of Germany, and residing at Dresden-A, Dobelnerstrasse 128, Germany, have

5 invented certain new and useful Improvements in Machines for Cutting Several Individual Cigarettes from Previously-Cut Cigarette Rods, of which the following is a specification.

10 The invention relates to a machine for cutting a multiplicity of previously cut cigarette rods into proper lengths for several individual cigarettes. The hitherto very limited capacity of all existing cigarette-making machines is considerably increased through this new machine so as to render the manufacture of cigarettes more profitable and productive.

15 The machine can be attached to any existing cigarette-making machine or used in combination with a new machine especially constructed for this purpose.

One form of the invention is illustrated in the accompanying drawing, in which Figure 1 is a side view of the entire machine; Fig. 2 is a side view from another direction, and Fig. 3 a view of the machine from above.

20 In the drawing 1 is a main shaft resting in bearings 2 and 3 and carrying the drum 4 which on its entire circumference is provided with grooves 5. Each of these grooves 5 can hold a cigarette rod of any desired length equal to the total length of a multiplicity of individual cigarettes. 6 are metallic guide bands which keep the cigarette rods in position during the rotation of the drum; and 7 is a device for putting the cigarette rods, one after the other, into 25 the corresponding grooves 5 of the drum 4.

The feeding device may be of any of the existing types and the modification shown in accompanying drawing is nothing but a mere diagrammatic arrangement to point 30 out the spot where the feeding device for cigarettes is attached. 8 is a curved guide for adjusting the position of the cigarettes in the drum 4, and 9 are circular knives arranged so as to cut the cigarette rods in 35 the drum at a certain definite point.

It is evident that one, two or more circular knives may be arranged at the proper distance from each other to cut simultaneously the cigarette rods into proper lengths 40 for two, three or more individual cigarettes.

10 is an endless conveyor belt which at 11 receives the cigarettes dropping out of the grooves 5 of the drum 4. 12 are the cigarette rods.

It is essential that the driving media for 60 the drum 4, the knives 9 and the endless conveyor belt 10 are controlled by the same main drive. The machine is driven in the following manner:

22 is a driving belt or chain which preferably is connected to the main drive of the cigarette-making machine and transmits power to the shaft 25, which drives a beveled pinion 21 which is in engagement with a second beveled pinion 26. The latter transmits its rotary motion to the spindle 27, to which is secured the worm 23 which cooperates with the worm wheel 24 on the shaft 1 of the machine, causing rotation of shaft 1 and drum 4.

25 The knives 9 are driven as follows: shaft 25 carries a disc wheel 20 which is connected to disc wheel 17 by means of a belt. Disc wheel 17 and disc wheel 16 are carried by the shaft 18 of the machine. 14 is a holder 80 on which shaft 13 rests which in turn carries knives 9 and disc 25^a. The latter is connected to disc 16 by means of a belt. As the result of above arrangement belt drive 22 causes the drum 4 and knives 9 to rotate, 85 while the speed of the knives may be regulated at will by selecting varying sizes of the discs 20, 17, 16 and 25^a.

90 In the same manner the conveyer belt may be rotated by suitable means from the main drive 22.

The arrangement works as follows: the previously cut cigarette rods which may be equal in length to two, three or more cigarettes of ordinary size are put into the drum 95 4 so as to fit one cigarette rod each into one of the grooves 5 of the drum 4, while the guides 8 cause the cigarette rods to be in the proper position before meeting the knife 9. During the rotation of the drum 100 4 the grooves 5 of the drum, one after another, are led past the feeding device 7 so as to permit each groove to receive one rod each and to convey the latter to the rotating knives 9. The rods are held in 105 their respective grooves by means of the guide bands 6 until they reach point 11 where they are cut into individual cigarettes of the proper length, drop on the guide band 10 and are carried away by the latter. 110

The invention is naturally not limited to the particular form shown and described above but can be applied broadly to a machine for cutting a multiplicity of previously cut cigarette rods into proper lengths for several individual cigarettes. The constructive arrangement referred to above may be varied in its essential parts, for instance instead of the rotating drum which 10 brings the cigarette rods to the knife any suitable feeding device may be employed in order to directly or indirectly deliver the cigarette rods by means of any suitable media within reach of the cutting or separating devices.

It has been found best to move the cigarette rods towards the cutting devices, but it would also be possible to move the cutting device towards the cigarette rods which 20 would then be in an axial position of rest.

If several cutting devices are employed, it is advisable, in view of the varying wear and tear of the individual cutting devices, to mount each cutting device separately and 25 adjustably in the direction of the cigarette rods; each cutting device may also be driven separately.

Furthermore, if several cutting devices are employed, they must be adjustable in axial direction in order to cut cigarettes of 30 varying length.

The adjustability of the said cutting devices may be obtained in any suitable manner.

35 It is one of the features of the invention that the machine may be attached to any existing cigarette-making machine without necessitating essential changes.

I claim:—
40 1. A machine for the manufacture of individual cigarettes from previously cut cigarette rods characterized by a rotating drum, provided at its periphery with grooves into which the said cigarette rods drop after leaving the cigarette-making ma-

chine; and furthermore means for adjusting the cigarette rods so that the ends thereof will lie in one plane, guide bands around a part of the circumference of the drum, circular knives for dividing the cigarette 50 rods into individual cigarettes, and a conveyor belt for carrying away the said individual cigarettes.

2. A machine for the manufacture of individual cigarettes from previously cut 55 cigarette rods characterized by a rotating drum, provided at its periphery with grooves into which drop the said cigarette rods after leaving the cigarette-making machine; furthermore a bent guide bar, guide 60 bands around a part of the circumference of the drum, circular knives for dividing the cigarette rods into separate, individual cigarettes, and a conveyor belt for carrying away the said individual cigarettes, while 65 the rotation of the drum, the knives, and the conveyor belt is caused by a common drive.

3. A machine for the manufacture of individual cigarettes from previously cut 70 cigarette rods characterized by a rotating drum, provided at its periphery with grooves into which drop the said cigarette rods after leaving the cigarette-making machine; and furthermore a bent guide bar, 75 guide bands around a part of the circumference of the drum, circular knives for dividing the cigarette rods into separate, individual cigarettes, and a conveyor belt for carrying away the said individual cigarettes, while for the purpose of cutting 80 cigarettes of varying length from one and the same rod the knives are axially adjusted to each other.

In testimony whereof I affix my signature in presence of two witnesses.

HEINRICH ELSNER.
